UNITED STATES PATENT OFFICE

2,549,640

BOILER CONSTRUCTION

Alonzo W. Ruff, New York, N. Y.

Application May 11, 1949, Serial No. 92,663

1 Claim. (Cl. 122—150)

1

My invention relates to improvements in a boiler construction and the principal objects of the invention are directed to the provision of a boiler construction which is efficient in its operation, is economically manufactured, and is adapted for many and various purposes.

According to my invention, the boiler components are preformed and are readily assembled to provide a composite structure. A multitude of adjacent water and heating surfaces are provided which result in rapid heat transfer and improved operating efficiency.

The novel construction of my invention is characterized by a cooling head or water chamber that is disposed at the end of the combustion chamber and is connected to the water space of the boiler. This chamber is so disposed that it is at right angles to the fire thereby to best pick up radiant heat. It is so constructed and connected to the water space that it increases water circulation in the boiler by a thermo-siphonic action.

As a special feature of the invention the water chamber functions to cool or protect the adjacent end plate of the boiler against excessive heat and to eliminate the necessity of the usual insulation.

All of the above objects I accomplish by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claim hereunto annexed and more fully described and referred to in connection with the accompanying drawings wherein:

Fig. 1 is a longitudinal sectional view through a boiler embodying the novel features of my invention, and

Fig. 2 is an end elevational view of the boiler shown in Fig. 1 taken at the right hand end thereof.

In the above mentioned drawing annexed here-to and forming a part of this specification, I have shown but one embodiment of my invention which is deemed preferable, but it is to be understood that changes and modifications may be made within the scope of the appended claim without departing from the spirit of the invention.

Referring now to the drawing more in detail, and referring more particularly to the preferred form of my invention selected for illustrative purposes, I have shown a shell 1 which is formed from sheet metal to have side walls 2 and upper

2

and lower walls 4 and 6 respectively which are preferably semi-circular in shape, as shown.

A wall 8 which may be called the inner forward wall extends between the side and upper and lower walls and will preferably be formed from sheet metal having its marginal edges secured to the walls of the shell by welding or the like at 10.

A wall 12 at the opposite or rear end of the shell extends between the walls thereof. A lower portion of this wall 12 is disposed inwardly from the rear end of the shell and has a horizontal portion 14 and a vertical portion 16 at the rear end of the shell. This wall 12 is secured to the shell by welding at its marginal edges as indicated by 18.

For convenience, the right hand end of the boiler is referred to as the rear end and the opposite end is referred to as the forward end.

20 A rear end plate 20 is provided which is removably secured to the shell by studs and nuts indicated by 22. The studs are secured to and extend forwardly from an angle or angles 24 and 25 secured to the shell and horizontal portion 14 of end wall 16. This plate 20 is easily and readily secured to and removable from the boiler which is desirable to provide access thereto.

A transverse member 26 extends between and is secured to the side walls at the rear end of the shell and a rear plate or plates indicated by 28 are secured to the rear end of the shell by studs and nuts as described in connection with plate 20.

It will be noted that a rear space 30 is provided 35 between the lower portion of wall 12 and plate 20 and that a forward space 32 is provided between wall 8 and plate or plates 28.

A combustion chamber 34 is provided which is preferably in the form of an elongated tube. 40 Its forward end extends through the rear inner wall 12 and its forward end extends through inner wall 8 as shown.

This member 34 is secured to walls 8 and 12 and to member 28 as by welding at 36, 38 and 40, 45 all as is shown.

A baffle 42 is disposed below the combustion chamber 34 which extends horizontally, as shown, and may be supported by member 34 by being welded thereto, or supported in any other well known manner.

A plurality of tubes 44 extend between and through the walls 8 and 12 and have opposite ends secured thereto as by welding at 46 and 48, as shown.

55 Stay rods 50 extend between the side walls 2 and have opposite ends secured thereto. Other stay rods 52 extend between wall 8 and portion 16 of wall 12 and have opposite ends secured thereto.

60 A water compartment 54 is provided in the space 30. It has lower hollow connections 56 extending through and secured to wall 12 and upper hollow connections 58 similarly extending to and

connected to said wall 12. A hollow stay member 55 extends between walls 57 and 59 of the member 54 and plate 20 is provided with an opening 21 in register with the stay member. A cover plate 23 is provided for movement on said plate 20 so as to be movable to and from the opening 21. The member 54 is disposed at the end of the combustion chamber so as to be at right angles to the fire and to thereby most efficiently pick up heat.

Member 54 connected to the water space of the boiler functions with a thermo siphonic action to circulate water thereby to increase the overall efficiency and capacity of the boiler and for best results it is connected at a point near the bottom of the boiler, as shown.

As an added function, member 54 acts to keep the adjacent plate 20 cool thereby reducing the amount of insulation usually required at the end of the boiler if not eliminating the same entirely. The stay tube provides a peek hole directly to the combustion chamber which is highly desirable, the water around the stay keeping it cool while the peek hole tube performs the function of a stay.

An outlet 60 is provided in the upper wall 4 and an inlet 62 is provided in the lower wall 6. The boiler may be used for hot water or steam and the outlet may be connected to any desired system from which the return thereof is connected to member 62.

A connection 66 is provided for conducting flue gases to a stack and the forward plate 28 is provided with an opening 68 for a fuel burner. An outlet 70 is provided in lower wall 6 which may be used for draining the boiler.

Although not shown, refractory material may, if desired, be employed in the combustion chamber, and a fuel burner of any desired form may be disposed on the plate or plates 68 and extended into the combustion chamber.

With the boiler connected in a system and containing water and a fuel burner in the combustion chamber 34, the products of combustion and hot gases extend in the direction of arrows *a* to the flue connection 66.

Water surrounds the combustion chamber 34 and tubes 44 and is contained within water chamber 54. The hot gases impinge the walls of the chamber 54 at right angle to the combustion chamber and tubes for the transfer of heat directly to the water for quick and efficient heating.

The member 54 brings about rapid water circulation while at the same time it functions to cool the plate 20 and provides a peek hole as set forth heretofore.

Return water to the boiler enters inlet 62 and is deflected by baffle wall 42 longitudinally and transversely upwardly and around the combustion chamber rather than by directly impinging said chamber.

The wall 14 closing the upper end of space 30 underlies the upper portion of the water space to aid in the transfer of heat and efficiency in operation.

It will be observed that the plates 20 and 28 facilitate ready and easy access to the boiler, particularly the tubes, inasmuch as they are removable, while efficiency is brought about by the large area of heating surfaces in proportion to the volume of water.

The invention may be embodied in other specific forms without departing from the essential char-

acteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claim are therefore intended to be embraced therein.

What it is desired to claim and secure by Letters Patent of the United States is:

A boiler construction comprising in combination, a longitudinal shell having side and upper and lower walls, a rear wall secured to the said walls of the shell and having a lower portion disposed inwardly and forwardly from an upper portion thereof, a rear plate secured to the rear ends of the side and lower walls of the shell cooperating with the last mentioned walls and lower portion thus providing a combustion space, a forward inner wall secured at marginal edges to the side and upper and lower walls and spaced inwardly from the forward ends of said walls, plate means secured to the forward ends of said upper and side and lower walls and forwardly of said forward inner wall thus providing a flue space, said plate means being provided with a combustion chamber opening, a longitudinal combustion tube having a forward end connected to said plate means around the opening therein and a rear end extending through and secured to the lower portion of the rear wall and opening into said combustion space inwardly of said rear plate, separate longitudinal flue tubes disposed at the sides of and above said combustion tube and having opposite ends extending through and secured to the lower portion of the rear wall and forward inner wall and opening into the spaces adjacent thereto, said upper wall provided with an outlet and said lower wall provided with an inlet disposed below said combustion tube and between the lower portion of the rear wall and the forward inner wall, and a baffle plate disposed transversely between said combustion tube and inlet, all adapted and arranged whereby a water space is provided around said combustion tube and flue tubes and over the space between said rear plate and lower portion of the rear wall, a water compartment disposed in the space between the rear plate and lower portion of the rear wall and rearwardly of and spaced from the rear end of said combustion chamber, and hollow connections extending from upper and lower sides of said compartment and having ends extending through and secured to the lower portion of the rear wall.
